Application February 13, 1928, Serial No. 253,976

19 Claims. (Cl. 196—48)

The present invention relates to improvements in the art of pressure distillation of hydrocarbon oils heavier than gasoline for the production of hydrocarbons of the gasoline range boiling points therefrom. It will be fully understood from the following description illustrated by the accompanying drawings, in which:

Figure 1 illustrates, partly in section and in part diagrammatically, apparatus suitable for carrying out the invention; and

Fig. 2 illustrates a modified form of apparatus in which certain variant forms of the invention may be carried out.

Referring more particularly to Fig. 1, the numeral 5 indicates a suitable oil container, preferably a horizontal, cylindrical shell or still adapted to withstand high internal pressure and to contain a substantial body of oil undergoing treatment. The shell or still 5 is mounted upon a suitable furnace setting 6, and is protected from the direct heat therefrom. Within the furnace setting there are provided a large number or bank of inclined tubes 7, the lower ends of which communicate with a lower header 8 and the upper ends of which communicate with an upper header 9. The lower header 8 communicates with a vertical pipe 10 which extends upwardly out of the furnace setting through the wall of the shell 5 and for a short distance therewith. The upper end of this tube or pipe 10 forms a seat for a closure member 11 mounted on the stem of a rod 12 threaded through a boss 13 on the upper part of the shell 5, the rod being operated by a hand wheel 14. It is readily apparent that, by operation of the rod 12, the upper end of the tube or pipe 10 may be closed to prevent communication with the contents of the shell 5 or may be opened to permit free communication therewith.

The upper header 9 likewise communicates with an upright pipe or tube 15 which enters the shell 5. The pipe 15 is surmounted by a hood or bell 16, the bottom of which is below the outlet of pipe 15.

From the upper part of the shell 5 the vapor outlet 17 communicates with a suitable reflux condenser or dephlegmator 18, illustrated diagrammatically. Reflux condensate formed therein is returned by the pipe 19 to the interior of the pipe 10 in the upper portion thereof. Vapors uncondensed in the reflux condenser 18 are discharged to a suitable final condenser and pressure controlling means, such as are commonly employed in the art and are not shown herein.

From a point above the bottom of the shell 5, a conduit 20, provided with a pressure release valve

21 and control valves 22, leads to a conduit 23, preferably formed with gradually expanding portions and opening into a reduced pressure drum or chamber 24. Within the drum 24, the conduit 23 opens downwardly above a deflector 25 some 5 distance above the bottom of the drum. In the upper portion of the drum there are provided a plurality of baffle plates 26 of any suitable form, or other suitable means for preventing entrainment of unvaporized liquids by the vapors leaving the drum. From the upper portion of the drum, the vapor conduit 27 leads vapors to the lower portion of a column or tower 28, illustrated diagrammatically as a bubble tower. The plates in the tower 28 may be of any desired form.

At a suitable intermediate point in the tower 28, the feed pipe 29 enters and may be employed for the supply of a hydrocarbon oil cooling medium or for the supply of fresh oil fed to the unit. A second supply pipe 30 enters the upper portion of 10 the tower and may be employed for supplying thereto a cooling medium of a lower range of boiling points, such as, for example, a condensate from the vapors evolved from the tower 28. From the upper portion of the tower, a vapor conduit 31 leads to any suitable condensing means (not 15 shown).

Condensate formed in the fractionating column or tower 28 and collected in the base thereof is withdrawn through valved pipe 32 and forced by 30 pump 33 through the valved pipe 34 to an intermediate point in the fractionating column 18, from which it passes, together with reflux condensate, through pipe 19 into the large pipe 10 25 extending from the lower header 8 in the furnace into the still 5.

From the base of the drum 24, unvaporized oil is discharged through the valved pipe 36 and forced by pump 37 through the pipe 38. The latter communicates with a pipe 39 provided with control valve 40 leading to a tar cooler or heat exchanger 41, from which the cooled unvaporized oil or tar is discharged through the line 42. The pipe 38 also communicates with a line 43 provided with control valve 44 through which any 40 desired portion of the unvaporized oil or the tar may be directed to the interior of the shell 5.

In carrying out an operation in accordance with the present invention, employing the apparatus of Fig. 1 as hereinbefore described, the still is 50 initially charged with oil to a level substantially above the tops of the pipes 10 and 15, said pipes, the headers 8 and 9 and the inclined tubes 7 being entirely filled. With a still of ordinary dimensions, say 30 feet in length and 10 feet in

diameter, a suitable initial charge is 12,000 to 13,000 gallons. The rod 12 is operated to open the upper end of the pipe 10, so that the entire contents of the still may be circulated and brought up to cracking temperature by the furnace heat applied to the inclined tubes 7. The stock initially charged into the still may suitably be of the gas oil type and have a gravity of say 30 to 33° A. P. I.

10 After the contents of the shell 5 have been brought to cracking temperature, for example, 725 to 750° F., a suitable superatmospheric pressure being maintained thereon, the valve 21 is opened to permit the flow under reduced pressure 15 of a certain proportion of the contents of the still through the pipe 20 and conduit 23 leading into the drum 24. In the drum 24 a separation of vapors from unvaporized oil takes place, the vapors passing through conduit 21 into the column 28. In order to effect a partial cooling of the 20 vapors in the column 28, oil, such as the stock which it is desired to feed into the unit during operation, is fed in through the pipe 29 and is 25 itself in part preheated by the vapors passing through the column. This feed may be suitably a gas oil of characteristics similar to that charged into the still, although, as hereinafter pointed out, the cold stock fed into the unit in this manner may be of widely varying characteristics, 30 crude oil, for example, being suitable. The unvaporized portion of the feed, preheated by the vapors in the column 28 together with the condensate formed from such vapors is withdrawn through the pipe 32 and forced by the pump 33 35 through the conduit 34 and into dephlegmator 18, from which it passes with the reflux condensate through pipe 19 into the depending pipe 10, which is then cut off from communication with the contents of the still by seating the closure member 11. In the initial stages of the operation, after 40 discharge of liquid products has begun from the shell 5, the entire quantity of tar or unvaporized oil from the lower portion of the drum 24, discharged through the pipe 36 is forced by the pump 37 through the line 43 back into the shell. During this portion of the operation, it will be 45 noted that the entire unvaporized portion of the liquid removed from the still remaining in the drum 24 is returned directly to the shell or still 50 and the condensate from the vapors given off from the drum 24 is returned together with the fresh feed stock or the unvaporized portion thereof to the interior of the pipe 10, to pass through the heating tubes 7 and the ascending pipe 15 into 55 the body of the still. At the same time, the reflux condensate formed in the column 18, being the portion of the vapors evolved from the still heavier than the desired distillate product, is returned through the pipe 19 directly to the interior of the depending pipe 10. Under these 60 conditions of operation, the temperature of the oil in the depending pipe 10 is substantially lower than that in the pipe 15 and in the shell 5.

Operation in the manner described is continued 65 until the contents of the shell or still 5 have reached the conditions which it is desired to maintain throughout the operation. For example, with an initial charge of type of gas oil having a gravity of 33° A. P. I., the stock in the shell 70 may reach an operating temperature of, say 735° F. After this desired point has been reached, a certain proportion of the tar or bottoms remaining unvaporized in the drum 24 may be discharged through the valved pipe 38 and the tar 75 cooler or heat exchanger 41, the amount so dis-

charged being controlled to maintain the liquid in the still 5 of the desired character. The amount of fresh feed stock added to the system through the supply pipe 29 is controlled to maintain a substantially constant volume of oil in the shell 5; that is, it is substantially equal in amount, to the distillate drawn off from the vapors leaving the still after passing the dephlegmator 18 and the light distillate formed from the vapors leaving the column 28 through the vapor line 10 15 together with the tars or bottoms discharged through line 39.

In order that the conditions prevailing in the unit may be clearly understood during its normal operation after a desired running condition has 20 been reached, the following conditions are set forth as they exist in a typical operation in a still of the capacity referred to above, in which the stock initially charged was a 33° gravity oil of the character of gas oil, about 13,000 gallons 25 being held in the shell, pipes 10 and 15, headers 8 and 9 and inclined tubes 7. After normal running conditions were attained, the liquid contents of the still were at a temperature averaging about 735° F., a pressure of 96 lbs. being maintained thereupon, and rapidly attained a gravity of 25 to 20° A. P. I., subsequently falling slowly in gravity and the tar or unvaporized oil drawn from drum 24 had a Saybolt Furol viscosity of 30 35 to 60 at 122° F.

The temperature of the descending oil in the pipe 10 is not higher than 650° F. and that in the ascending pipe 15 just below the bottom of the shell 5 averages about 790° F. 400 to 425 gallons per hour of distillate are taken off from the 35 vapors leaving the shell after reflux condensate has been removed therefrom in a dephlegmator 18, such reflux condensate being returned to the pipe 10. Approximately 1,650 gallons per hour of the contents of the shell are removed through the line 20, of which about 350 gallons per hour remain unvaporized in the drum 24 and are withdrawn therefrom. Of this, approximately 215 gallons per hour are returned through the line 43 to the shell 5. The remainder, about 135 gallons per hour, is discharged from the system. The temperature in the drum 24, which is approximately at atmospheric pressure, is about 540° F. The vapors discharged through the line 27, which are approximately equivalent to 1,300 50 gallons per hour of oil, then enter the tower 28, into which about 650 gallons per hour of fresh feed are supplied through the pipe 29. The fresh feed and condensate formed in the tower 28, which together amount to about 1,800 gallons per hour are returned to the pipe 10 through the line 34, dephlegmator 18 and pipe 19. It will thus be seen that the amount of oil returned to the still through the lines 34 and 43 is substantially 55 equivalent to the sum of the net distillate withdrawn from the still and the tar or unvaporized oil discharged through the line 20.

The above example is by way of illustration, and the invention is not limited to the use of the stocks and pressure conditions set forth therein. 65 Stocks of other characteristics may be charged or fed into the still, and the stocks fed in during normal operation may vary from that initially charged. The pressure may also be widely varied.

By operating in the manner described, we have 70 been able to run continuously for long periods of time and with great economy of operation. Furthermore, in operating in accordance with the present invention, the desired heating of the oil is effected without the use of excessively long 75

fired coils involving great friction losses and pressure drops and without the involved and expensive pumping arrangements that are ordinarily required in connection therewith.

It is readily apparent that the operation may be modified in many respects within the scope of the present invention. Thus the quantity and character of the unvaporized liquid or tar formed in and withdrawn from the flash drum 24 may be controlled by varying the extent of vaporization taking place therein, any such variation producing a corresponding result in the character of stock in the shell or still. If desired, steam or other vapor may be introduced in the body of liquid therein or into the stream of liquid entering the drum. In Fig. 1 of the drawings suitable means are provided for using the vapor product present in the still for this purpose. Thus vapors from the still may pass through line 75 controlled by valve 76 directly to the line 20 through which the liquid from the still passes to drum 24. A similar result may be secured by increasing the difference in pressure between the still and the drum 24, as by raising the pressure in the former.

It is apparent that if increased proportions of the liquid withdrawn from the still are vaporized in drum 24, larger amounts of condensate are formed in tower 28 and returned to the system, thus permitting the elimination of a greater proportion or of all of the tar or residuum formed in drum 24.

Figure 2 illustrates a modified form of construction, in accordance with the present invention. In the form illustrated in this figure, the numeral 55 indicates a shell or still, 56 the furnace setting, 57 the inclined heating tubes, 58 the lower header and 59 the upper header, these parts being similar in arrangement and construction to the corresponding parts as illustrated in Fig. 1.

The lower header 58 communicates with the vertical pipe 60 which extends upwardly into the shell 55 and is closed off from the body of the shell by the closure 61 operated by the rod 62. The upper header 59 is connected by the vertical pipe 63 with an enlarged pipe section 64 within the still, open at the top and surmounted by a bell or hood 65 which directs any material issuing from the pipe section 64 in a downward and lateral direction in the shell. The pipe member 64 is connected by a conduit or pipe section 66 with the descending pipe 60. Vapors from the shell or still 55 pass out through the vapor line 67 into the reflux column or dephlegmator 68 in which the portions heavier than the desired distillate products are condensed by cooling. The reflux condensate formed is returned through the line 67 in countercurrent to the vapors issuing from the still, the reflux condensate dropping into a funnel-shaped opening 69 of a pipe 69^a, by which it is led to the interior of the enlarged pipe section 64.

The arrangement in connection with the shell 55 for withdrawal of liquid from the shell, reduction of pressure upon and partial vaporizing of this liquid, and return of unvaporized liquid (when desired) are substantially similar to those shown in connection with Figure 1 and the respective parts are indicated by the same numerals with the suffix ^a. In general the operation conducted in these parts is the same as already described in connection with Fig. 1. In the form shown in Fig. 2, condensate from tower 28^a together with fresh feed supplied thereto is forced

through line 34^a directly to a downwardly directed nozzle 35^a in conduit 60.

In the operation carried out in the apparatus in accordance with Fig. 2, it will be noted that there is a continuous withdrawal of liquid from the shell or still through line 20^a, the pressure is reduced upon the material so withdrawn, the vaporized portion is partly condensed and the resulting condensate returned to the interior of the vertical pipe 60 communicating with the bottom header 58 and a part of the unvaporized portion of the liquid withdrawn from the shell 55 may be returned to the shell through the line 43^a. In these respects the operation is essentially similar to that described in connection with Fig. 1. Similarly fresh feed is supplied to the system in essentially the same manner as in the operation previously described. It will be noted that the pipe 66 permits the recirculation of a portion of the material which has already passed through the heating pipes 57 and as a consequence, a higher average temperature is maintained in the pipe 60 in the operation conducted in accordance with Fig. 2 than is maintained in the pipe 10 of the operation of Fig. 1.

We claim:

1. In apparatus for distilling hydrocarbon oils under pressure for the production of lighter hydrocarbon oils of the character of gasoline, a container, a bank of inclined tubes below said container, means for heating said tubes, upper and lower headers communicating with the upper and lower ends of said tubes, conduits extending from said upper and lower headers into the said container, said conduits extending above the lowermost portion of said container, means for cutting off communication between the interior of the container and the conduit extending to the lower header, means for withdrawing liquid from the interior of said container, means for vaporizing a portion of the liquid so removed, and means for supplying unvaporized portions of removed liquid directly to the container.

2. In apparatus for distilling hydrocarbon oils under pressure for the production of lighter hydrocarbon oils of the character of gasoline, a container, a bank of inclined tubes below said container, means for heating said tubes, upper and lower headers communicating with the upper and lower ends of said tubes, conduits extending from said upper and lower headers into the said container, said conduits extending above the lowermost portion of said container, means for cutting off communication between the interior of the container and the conduit extending to the lower header, means for withdrawing liquid from the interior of said container, means for vaporizing a portion of the liquid so removed, and means for supplying a portion of the unvaporized material directly to the container, means for condensing at least a portion of the vaporized part of said liquid, means for supplying condensate thus formed within the conduit communicating with the lower header.

3. In apparatus for distilling hydrocarbon oils under pressure for the production of lighter hydrocarbon oils of the character of gasoline, a container adapted to contain a body of liquid hydrocarbon oil undergoing cracking, a bank of inclined tubes below said container, means for heating said tubes, upper and lower headers communicating with the upper and lower ends of said tubes, conduits extending from said upper and lower headers into the said container, said conduits extending above the lowermost portion

of said container to a point below the level of liquid oil therein, means for cutting off communication between the interior of the container and the inlet opening of the conduit extending 5 to the lower header, means for introducing oil into said conduit from the exterior of the chamber below said closure means, means for withdrawing oil from said container from a level below the tops of said conduits, means for distilling the 10 withdrawn oil and means for returning liquid unvaporized during such distillation directly to said container.

4. The method of effecting the distillation of hydrocarbon oils under pressure for the production 15 of low boiling hydrocarbon products such as gasoline, which comprises maintaining a body of oil under pressure at conversion temperature, separating evolved vapors while maintaining them under pressure, cooling the evolved vapors 20 and separating therefrom condensed hydrocarbons heavier than the desired products, discharging liquid from said body of oil through a conduit of restricted cross section into an enlarged chamber, reducing the pressure within said conduit at an intermediate portion thereof, separately removing and discharging a portion of vapor from said body of oil into said conduit in a portion thereof under reduced pressure, and removing and separately cooling the vapors evolved 25 from said enlarged chamber.

5. In apparatus for distilling hydrocarbon oils under pressure for the production of lighter hydrocarbon oils of the character of gasoline, a 30 container, a plurality of inclined pipes below said container, headers at each end of said pipes, conduits connecting said headers with the interior of said container, said conduits extending above the lowermost portion of the container and having their tops below the intended liquid level 35 therein, a closure means for the conduit communicating with the lowermost header, and a bell surmounting the conduit communicating with the uppermost header.

6. The method of effecting the distillation of hydrocarbon oils under pressure for the production 40 of low boiling hydrocarbon products such as gasoline which comprises maintaining a body of oil under pressure at conversion temperature, separately withdrawing evolved vapors from said 45 body while maintaining them under pressure, passing said vapors directly to a fractionating operation, separately discharging liquid from said body of oil through a conduit of restricted cross-section into an enlarged chamber, reducing the 50 pressure within said conduit at an intermediate portion thereof, withdrawing another portion of the evolved vapors from said oil body and passing them directly from said oil body into said conduit in the portion thereof under reduced 55 pressure.

7. In apparatus for distilling hydrocarbon oil under pressure for the production of lighter hydrocarbon oils of the character of gasoline, a 60 container, an elongated heated passageway, conduits extending from each end of said heated passageway into said container above the lowermost portion thereof, said conduits having their tops below the intended liquid level in said container, one of said conduits serving to conduct oil from said container to said heated passageway and the other of said conduits serving to return oil from the said heated passageway to said container, a closure means for the said conduit for 65 conducting oil to said heated passageway, and a 70

bell surmounting the top of the other of the said conduits.

8. The method of effecting the distillation of hydrocarbon oils under pressure for the production 75 of low boiling hydrocarbon products such as gasoline which comprises maintaining a body of oil under pressure at conversion temperature, separately withdrawing evolved vapors from said body and passing them directly to a fractionating operation, separately withdrawing liquid from 80 said oil body and discharging the same into a separate zone maintained under substantially lower pressure, and withdrawing another portion of the vapors evolved from said oil body and flowing them directly from said oil body into said low 85 pressure zone in admixture with the said liquid flowing thereto from said oil body.

9. The method of effecting the distillation of hydrocarbon oils under pressure for the production 90 of lower boiling products which comprises maintaining in an enlarged chamber a body of oil under pressure at conversion temperature, separately removing evolved vapors from said enlarged chamber and subjecting them to fractionation to condense constituents thereof heavier 95 than the desired low boiling products, withdrawing the fractionated vapors and condensing them, withdrawing the condensate from said fractionating operation and passing it through a heated passageway to heat it to cracking temperature, discharging heated products from said passageway into said enlarged chamber, separately withdrawing liquid oil from said enlarged chamber and discharging it into a distilling zone maintained under a materially reduced 100 pressure, withdrawing evolved vapors from said enlarged chamber and intimately contacting them with the liquid oil entering said low-pressure distilling zone, separately withdrawing unvaporized liquid oil from said low pressure distilling zone and returning it directly to said enlarged chamber, separately withdrawing evolved vapors from said low pressure distilling zone and passing them to a fractionating operation separate from the aforesaid first named fractionating 105 operation, withdrawing condensate from the said second named independent fractionating operation and passing it through said heated passageway in admixture with the first named condensate.

10. The method of effecting the distillation of hydrocarbon oils under pressure for the production 110 of lower boiling products which comprises maintaining in an enlarged chamber a body of oil under pressure at conversion temperature, separately removing evolved vapors from said enlarged chamber and subjecting them to fractionation to condense constituents thereof heavier than the desired low boiling products, withdrawing the fractionated vapors and condensing them, withdrawing the condensate from said fractionating operation and passing it through a heated passageway to heat it to cracking temperature, discharging heated products from said passageway into said enlarged chamber, separately withdrawing liquid oil from said enlarged chamber and discharging it into a distilling zone maintained under a materially reduced pressure, withdrawing evolved vapors from said enlarged chamber and intimately commingling them with the liquid oil entering said low pressure distilling zone, separately withdrawing unvaporized liquid oil from said low pressure distilling zone and returning it directly to said enlarged chamber, separately withdrawing evolved vapors from said 115

low pressure distilling zone and passing them to a fractionating operation separate from the aforesaid first named fractionating operation, withdrawing condensate from the said second 5 named independent fractionating operation and passing it through a heated passageway wherein it is heated to cracking temperature and thereafter discharging cracked products from the latter passageway into said enlarged chamber.

10 11. The method of effecting the distillation of hydrocarbon oils under pressure for the production of lower boiling products which comprises maintaining in an enlarged chamber a body of oil under pressure at conversion temperature, 15 separately removing evolved vapors from said enlarged chamber and subjecting them to fractionation to condense constituents thereof heavier than the desired low boiling products, withdrawing the fractionated vapors and condensing them, 20 withdrawing the condensate from said fractionating operation and passing it through a heated passageway to heat it to cracking temperature, discharging heated products from said passageway into said enlarged chamber, separately with- 25 drawing liquid oil from said enlarged chamber and discharging it into a distilling zone maintained under a materially reduced pressure, withdrawing evolved vapors from said enlarged chamber and intimately contacting them with the 30 liquid oil entering said low-pressure distilling zone, separately withdrawing unvaporized liquid oil from said low pressure distilling zone and returning it directly to said enlarged chamber, separately withdrawing evolved vapors from said 35 low pressure distilling zone and passing them to a fractionating operation separate from the aforesaid first named fractionating operation, introducing relatively cool fresh oil into the latter fractionating operation and contacting the said 40 fresh oil with the vapors therein to effect fractionation of the said vapors, withdrawing the resulting condensate-fresh oil mixture from the latter fractionating operation and contacting it with the vapors undergoing fractionation in said 45 first named fractionating operation.

12. The method of effecting the distillation of hydrocarbon oils under pressure for the production of lower boiling products which comprises maintaining in an enlarged chamber a body of oil under pressure at conversion temperature, 50 separately removing evolved vapors from said enlarged chamber and subjecting them to fractionation to condense constituents thereof heavier than the desired low boiling products, withdraw- 55 ing the fractionated vapors and condensing them, withdrawing the condensate from said fractionating operation and passing it through a heated passageway to heat it to cracking temperature, discharging heated products from said passageway into said enlarged chamber, separately with- 60 drawing liquid oil from said enlarged chamber and discharging it into a distilling zone maintained under a materially reduced pressure, withdraw- 65 ing evolved vapors from said enlarged chamber and intimately commingling them with the liquid oil entering said low pressure distilling zone, separately withdrawing unvaporized liquid oil from said low pressure distilling zone and returning it directly to said reaction zone, sepa- 70 rately withdrawing evolved vapors from said low pressure distilling zone and passing them to a fractionating operation separate from the aforesaid first-named fractionating operation, withdrawing condensate from the said second 75 named independent fractionating operation and

bringing it into direct contact with the vapors undergoing fractionation in said first named fractionating operation.

13. A hydrocarbon oil cracking process which comprises passing the oil through a heating zone and heating the same therein to cracking temperature under pressure, discharging the heated oil into a vapor separating zone and separating the same therein into vapors and residual oil, dividing the vapors into a first vapor stream and a second vapor stream, dephlegmating the first vapor stream and returning the resultant reflux condensate to the heating zone, finally condensing the dephlegmated vapors as a product of the process, removing the residual oil from the separating zone and flash distilling the same by lowering the pressure thereon, and passing said second vapor stream directly from the separating zone into intimate contact with the residual oil undergoing flash distillation to assist the vaporization thereof. 15

14. In apparatus for distilling hydrocarbon oils under pressure for the production of lighter hydrocarbon oils of the character of gasoline, a container, a bank of inclined tubes below said container, means for heating said tubes, upper and lower headers communicating with the upper and lower ends of said tubes, conduits extending from said upper and lower headers into the said container, said conduits extending above the lowermost portion of said container, and means for cutting off communication between the interior of the container and the open end of the conduit extending to the lower header, means for withdrawing liquid from the interior of said container, means for distilling the withdrawn liquid, means for returning liquid unvaporized during such distillation directly to said container, and means for supplying oil to be treated within the conduit leading to the lower header and at a point beyond said closure means. 20 25

15. In apparatus for distilling hydrocarbon oils under pressure for the production of lighter hydrocarbon oils of the character of gasoline, a container, a heating zone, a conduit for conveying oil from the container through the heating zone and back to the container, said conduit extending into the interior of said container, closure means for cutting off communication between the container and the inlet end of said conduit, means for withdrawing liquid from said container, means for distilling such liquid, means for returning liquid unvaporized during such distillation directly to said container, means for withdrawing vapors from the container and condensing portions thereof heavier than the desired gasoline product, and means for introducing the resulting condensate into the conduit below said closure means and ahead of said heating zone. 45 50 55

16. In apparatus for distilling hydrocarbon oils under pressure for the production of lighter hydrocarbon oils of the character of gasoline, a container, a heating zone, a conduit for conveying oil from the container to the heating zone and back to the container, said conduit extending into the interior of said container, closure means for cutting off communication between the container and the inlet end of said conduit, means for withdrawing liquid oil from said container, means for distilling such oil, means for returning liquid unvaporized during such distillation directly to said container, means for withdrawing vapors from the container, means for effecting heat exchange between the removed vapors and fresh oil, thereby condensing the portions of said vapors heavier 60 65 70 75 80

than the desired gasoline products and heating said oil, and means for introducing the said heated oil and the condensate into the conduit below said closure means and ahead of said heating zone.

5 17. In apparatus for distilling hydrocarbon oils under pressure for the production of lighter hydrocarbon oils of the character of gasoline, a container, a heating zone, a conduit for conveying oil from the container to the heating zone and back 10 to the container, said conduit extending into the interior of said container, closure means for cutting off communication between the container and the inlet end of the conduit, means for withdrawing liquid oil from said container, means for distilling such oil, means for returning liquid unvaporized during such distillation directly to said container, means for withdrawing vapors from the container, means for contacting the vapors thus withdrawn with fresh oil, thereby condensing 15 the portions of said vapors heavier than the desired gasoline products and heating the said oil, and means for introducing the said oil and condensate into the conduit below said closure means 20 and ahead of said heating zone.

18. A method of effecting the distillation of hydrocarbon oils under pressure for the production of low boiling hydrocarbon products such as gasoline which comprises maintaining a body of oil under pressure and at conversion temperature, 25 continuously flowing oil to be subjected to conversion conditions through a heating zone where-

in it is brought to conversion temperature and into said body of oil, continuously and separately removing evolved vapors from said oil body and passing them to a condensing operation, continuously removing liquid from said body of oil, reducing the pressure to vaporize a portion thereof, withdrawing evolved vapors from said body of oil and intimately contacting them with the liquid being vaporized, heating condensed fractions of said separately removed vapors heavier than the desired low boiling products and thereafter discharging them into said body of oil.

19. A hydrocarbon oil cracking process which comprises passing the oil through a heating zone and heating the same therein to cracking temperature under pressure, discharging the heated oil into a vapor separating zone and separating the same therein into vapors and residual oil, dividing the vapors into a first vapor stream and a second vapor stream, dephlegmating the first 15 vapor stream to separate reflux condensate therefrom, finally condensing the dephlegmated vapors as a product of the process, removing residual oil from the separating zone and vaporizing the same, and passing said second vapor stream directly from the separating zone into intimate contact with the residual oil undergoing vaporization to assist in the vaporization thereof.

Henry Van Arsdale,
Acting Commissioner of Patents.

than the desired gasoline products and heating said oil, and means for introducing the said heated oil and the condensate into the conduit below said closure means and ahead of said heating zone.

5 17. In apparatus for distilling hydrocarbon oils under pressure for the production of lighter hydrocarbon oils of the character of gasoline, a container, a heating zone, a conduit for conveying oil from the container to the heating zone and back to the container, said conduit extending into the interior of said container, closure means for cutting off communication between the container and the inlet end of the conduit, means for withdrawing liquid oil from said container, means for distilling such oil, means for returning liquid unvaporized during such distillation directly to said container, means for withdrawing vapors from the container, means for contacting the vapors thus withdrawn with fresh oil, thereby condensing the portions of said vapors heavier than the desired gasoline products and heating the said oil, and means for introducing the said oil and condensate into the conduit below said closure means and ahead of said heating zone.

18. A method of effecting the distillation of hydrocarbon oils under pressure for the production of low boiling hydrocarbon products such as gasoline which comprises maintaining a body of oil under pressure and at conversion temperature, continuously flowing oil to be subjected to conversion conditions through a heating zone where-

in it is brought to conversion temperature and into said body of oil, continuously and separately removing evolved vapors from said oil body and passing them to a condensing operation, continuously removing liquid from said body of oil, reducing the pressure to vaporize a portion thereof, withdrawing evolved vapors from said body of oil and intimately contacting them with the liquid being vaporized, heating condensed fractions of said separately removed vapors heavier than the desired low boiling products and thereafter discharging them into said body of oil.

19. A hydrocarbon oil cracking process which comprises passing the oil through a heating zone and heating the same therein to cracking temperature under pressure, discharging the heated oil into a vapor separating zone and separating the same therein into vapors and residual oil, dividing the vapors into a first vapor stream and a second vapor stream, dephlegmating the first vapor stream to separate reflux condensate therefrom, finally condensing the dephlegmated vapors as a product of the process, removing residual oil from the separating zone and vaporizing the same, and passing said second vapor stream directly from the separating zone into intimate contact with the residual oil undergoing vaporization to assist in the vaporization thereof.

OSWALD C. BREWSTER. 30
MAX G. PAULUS.
ANDREW E. THOMPSON.

CERTIFICATE OF CORRECTION.

Patent No. 2,098,772.

November 9, 1937.

OSWALD C. BREWSTER, ET AL.

It is hereby certified that error appears in the printed specification of the above numbered patent requiring correction as follows: Page 5, first column, line 69, claim 12, for the words "reaction zone" read enlarged chamber; and that the said Letters Patent should be read with this correction therein that the same may conform to the record of the case in the Patent Office.

Signed and sealed this 25th day of January, 1938.

(Seal)

Henry Van Arsdale,
Acting Commissioner of Patents.
